(57) **CLAIM**

The ornamental design for a table, as shown and described.

DESCRIPTION

FIG. 1 is a perspective view of a table of the present invention;
FIG. 2 is a front and back view thereof;
FIG. 3 is a side view thereof;
FIG. 4 is a top view thereof;
FIG. 5 is a perspective view of an alternate embodiment of a
table of the present invention;
FIG. 6 is a front and back view thereof;
FIG. 7 is a side view thereof;
FIG. 8 is a top view thereof;
FIG. 9 is a perspective view of a second alternate embodiment
of a table of the present invention;
FIG. 10 is a front and back view thereof;
FIG. 11 is a side view thereof;
FIG. 12 is a top view thereof;
FIG. 13 is a perspective view of a third alternate embodiment
of a table of the present invention;
FIG. 14 is a front and back view thereof;
FIG. 15 is a side view thereof; and,
FIG. 16 is a top view thereof.
